UNITED STATES PATENT OFFICE.

FRANK E. LEITCH, OF STAMFORD, CONNECTICUT, ASSIGNOR TO STAMFORD WALL PAPER COMPANY, OF STAMFORD, CONNECTICUT, A CORPORATION OF DELAWARE.

DESIGN FOR WALL PAPER OR THE LIKE.

Application filed November 23, 1927. Serial No. 24,259. Term of patent 3½ years.

To all whom it may concern:

Be it known that I, FRANK E. LEITCH, a citizen of the United States, residing at Stamford, in the county of Fairfield and State of Connecticut, have invented a new, original, and ornamental Design for Wall Paper or the Like, of which the following is a specification, reference being had to the accompanying drawing, forming part hereof.

The single figure of the drawing is a plan view of a piece of wall paper showing my new design; it being understood that the design shown at the left of the drawing is duplicated in the blank space at the right.

I claim:

The ornamental design for wall paper or the like as shown and described.

FRANK E. LEITCH.
